UNITED STATES PATENT OFFICE.

ANDREW RUNSTETLER, OF PEORIA, ILLINOIS, ASSIGNOR TO SAMUEL D. COCHRAN, OF SAME PLACE.

IMPROVEMENT IN CONVERTIBLE CORN-PLANTERS.

Specification forming part of Letters Patent No. 116,493, dated June 27, 1871.

To all whom it may concern:

Be it known that I, ANDREW RUNSTETLER, of Peoria, in the county of Peoria and State of Illinois, have invented a new and Improved Convertible Corn-Planter; and I do hereby declare that the following is a full, clear, and exact description of the construction and operation of the same, reference being had to the accompanying drawing making a part of this specification, in which—

Figure 1 is a side elevation of corn-planter. Fig. 2 is a plan view of same. Fig. 3 is a side elevation of corn-stalk cutter as combined with the frame of planter. Fig. 4 is a plan view of the same.

Like letters in the different figures of the drawings indicate like parts.

My invention relates to an arrangement of parts by which the planter may be readily converted into a corn-stalk cutter, as will be hereinafter more fully explained.

A A are the side beams of the planter-frame, which are strengthened by the cross-pieces C D E. B is the axle; D, cross-piece under front of the box, in front of which is a clevis, d d, having perpendicular slots in each plate, in which is adjusted a bolt, which secures the heel of the tongue K at the required angle. E is a movable bar across the forward end of the frame, and bolted to the latter, and to which bar the clevises t t, carrying the forward ends of the runners, are attached. F is a lever for raising the runners from the soil, and pivoted at g to the box-bar G, and passing to the rear, and terminating in a cross foot-board, f f, and pivoted intermediately at f, in each arm of the shoe W, at the base of the seat-bars Z. H is the corn or dropper-box, of the usual pattern; I, the chute of the runners; I I, the runners; K, the tongue adjusted to clevis d, as described under reference letter D, above; L, the wheels; M, the upper plate of the oscillating part of the cut-off—a a being the cut-offs proper, whose front ends are rounded so as not to cut or damage the corn, and hollowed out beneath for a similar purpose. b b are the projecting elbows of the plate, which follow their respective cut-off a a, pushing the corn in the proper holes e e in the stationary plate N; M M, the lower plate of the oscillating part of cut-off, called the "slide," of similar size, and fastened to the upper plate M by means of screws at the sides,

and steadied by means of the dogs or clamps p p p p at the corners. This plate has two holes pierced in it at m m, where the dotted lines indicate them; they are, of course, in a line with those in the stationary plate N. The sliding dropper-plates M M M are united from either side of the machine by a link, and moved by a lever, d d, which oscillates transversely of the machine; N, the stationary intermediate plate part of the dropper mechanism, inclosed between the plates M M M, having perforations e e, which are set to any slight change of size by means of the adjusting-gauge P. This plate is fastened to the lower edges of the box, at either end. Y is an adjustable rolling scraper-rod, carrying at either end a knife for cleaning the wheels. Z represents the bars supporting the driver's seat, each resting in a shoe, W, bolted to the axle B, the shoes having each an arm, f, which carries the pin of the lever F; on these bars are set adjustable foot-rests, z z, which slide by means of a bolt and slots, and can be set to any height.

Having thus described the frame-work and other parts of the planter, the construction of which is peculiarly adapted for the purpose intended, I will now proceed to describe how the same may be readily converted into a corn-stalk cutter. To do this I remove the boxes H, lever F, and bar E, with the attached runners I I, and insert the corn-stalk cutter, by simply making the shorter beam E E take the place of E. This bar E carries the forward ends of the two parallel curved sides Q Q of the frame of the stalk-cutter in the clevises t t, being further kept steady by the uprights r r on the bar D, permitting the perpendicular motion of the latter. The rear end of the frame Q terminates with a rolling stalk-cutter, T, the axle of which rests in the end of the frame Q. It consists of four horizontal blades set in a circle. R R are two parallel levers pivoted to either end of the axle of the cutter T, each resting against a guide, u u, at each side of the planter-frame. By means of these levers the cutter is raised from the soil. S S are two similar parallel bars immovably fastened to either side of the upper part of the frame Q, and by which the work of the cutter is regulated.

To explain more particularly the manner of adapting the corn-stalk cutter to the frame of the planter, the bar E is unbolted and lifted off the frame A A, taking with it the boxes H H

and lever F, then introducing into the frame the cutter Q Q S T. The beam E E, carrying the forward ends of the beams Q Q, is placed in the place formerly occupied by the runner-bar E, and bolted to the frame. The pivoted levers R R rest between the guides u u attached to the ends of the bar B, (all shown in Figs. 3 and 4,) and in the slotted guides r r, on the bar D of the same. The levers S S are pressed by the feet of the driver, who sits on the seat on the standard Z, (which is removed,) to regulate the force of the revolving cutter T. The levers R R are operated in the same way for raising the cutter from its work, and can be thrown back or down until it lies as shown by the dotted lines.

Having thus fully described my invention, what I claim therein as new, and desire to secure by Letters Patent, is—

The convertible corn-planter, consisting of beams A A, removable beam E, stationary beam D provided with the uprights r r, and slotted clevis d, carrying the heel of the tongue K, axle B provided with the guides u u, seat-bars Z Z, with shoes w w constructed so as to afford a bearing for the pivots of box-lever F, all arranged and adapted to receive the parallel levers R R and foot-bars S S, and removable beam E E carrying the rotary corn-stalk cutter, substantially as described.

In testimony that I claim the foregoing I, ANDREW RUNSTETLER, have hereunto set my hand this 30th day of November, 1870.

ANDREW RUNSTETLER.
